UNITED STATES PATENT OFFICE.

CARL A. KELLOGG, OF BROOKLYN, NEW YORK.

PLATEN FOR PRINTING MACHINES.

Application filed December 15, 1919, Serial No. 344,956. Renewed November 29, 1921. Serial No. 518,641.

To all whom it may concern:

Be it known that I, CARL A. KELLOGG, a citizen of the United States, residing in the city of New York, borough of Brooklyn, county of Kings, and State of New York, have invented a certain new and useful Platen for Printing Machines, of which the following is a specification.

This invention is a platen for printing machines and is adapted to form one member of the printing couple adapted for rolling co-action during the periods of impression.

While numerous forms of platen, adapted to constitute one member of a printing couple, have been suggested, the curved face, with which most of said platens are provided, and which serves as the impression surface thereof, is formed on a true arc of a circle, developed from a common center through a given radius. Platens so constructed are found, in practice, to produce inferior results since, when subjected to rolling co-action with a form, the pressure of the platen on the form is not uniform throughout impression and, accordingly, uniform impressions do not result.

The prime object of the present invention is to provide a platen, the curved face of which is so formed that the platen may be operated by rigid actuating and guiding mechanism, and when so operated, the curved face of the platen will press with a uniform pressure upon all parts of the form from start to finish of impression.

A further object of the invention is to provide a light strong and durable construction, capable of operation at high speeds, regardless of the material from which the platen is constructed, and to so position and operate the platen that the direction of pressure along the entire surface of the platen is in a straight line between the point of contact of the platen with the form bed and the support of the platen.

Another object of the invention is to provide a platen which will be stiff and rigid and capable of operating on one or more forms whether positioned end to end, or side by side.

Features of the invention, other than those specified, will be apparent from the hereinafter detailed description taken in conjunction with the accompanying drawings.

In the accompanying drawings, I have illustrated one practical embodiment of the invention, but the construction therein shown is to be understood as illustrative only, and not as defining the limits of the invention.

Figure 1 is a top plan view of the platen embodying the present invention.

Figure 2 is a side elevation of the platen showing the manner of mounting it in a printing machine.

Figure 3 is an end elevation of the structure as shown in Figure 2, the supporting shaft of the platen being shown in section; and

Figure 4 is a diagrammatic view illustrating the operation of the platen.

In constructing the light, strong and rigid platen of this invention, it is preferably formed as shown in the drawings by a rigid curved plate 1 substantially rectangular in plan and provided at its opposite ends with upstanding brackets 2, the upper portions of which are formed into bearings 3. The curved plate 1 is preferably stiffened longitudinally and transversely by means of ribs 4, cast integral therewith, while the brackets 2 are stiffened by continuing the center longitudinal rib in the form of a web 5 upwardly on the inside of each bracket 2, to the bearings 3. By this construction a very strong and rigid platen is produced and one of extremely light weight, whereby the inertia of the platen during operation is minimized and it may be actuated at relatively high speeds without producing shocks, vibration or jar, and without springing during impression.

Associated with each lateral edge of the platen is a bearer 6 which is set into a recess 7 extending along the lower edge of the platen. Each bearer 6 is secured to one end of the plate 1 by machine screws or bolts 8 which pass through slots 9 in the bearers and thread into the plate 1. This bolt and slot connection is provided to allow of adjustment of the bearings, to regulate the pressure of the platen while on impression and, in practice, such adjustment is obtained by means of adjusting nuts 10, which work on screw threaded posts 11. Through the manipulation of these nuts the desired elevation and consequent pressure, may be readily had.

The platen is supported on and actuated

2 by a shaft 16 which is provided with off set or crank portions 17, so that, as the crank shaft 16 revolves in fixed bearings 18, which are adjustable toward and away from the platen, the platen will be raised and lowered in accordance with the positions of the cranks 17 of said shaft.

In the preferred manner of employing the platen of this invention, the bottom curved surface of the plate 1, constitutes the impression surface of the platen and positioned at either end of said platen and in a longitudinal medial line of the impression surface is a trunnion 19, adapted to co-operate with a fixed vertical guide in the machine to limit the movement of the trunnions 19 to sliding movement in a path at right angles to the face of the operating form.

20 When a platen is mounted on a crank shaft and guided for sliding movement in the manner described, it partakes of a peculiar gyrating or oscillating movement during operation, as will be clearly seen from Figure 4 of the drawings. The function of this movement of the platen is to adapt it for rolling co-action over the complementary member of the printing couple during impression and to move it free from the said 30 complementary member of the printing couple between impressions. When the crank shaft 16 rotates, the cranks 17 will travel through a circular path, the path of the axis of each crank 17 being shown in the dot and 35 double dash line 20 in Figure 4. The axis of this circular path is the axis of rotation of the crank shaft 16 which is designated in Figure 4 by 21. In Figure 4, the center of the trunnion 19 is designated by 22, and the 40 position of the platen, when the crank is on bottom dead center with the members of the printing couple on the center of impression, is shown in full lines 23. The dash line position 24 shows the platen at the instant it 45 commences the impression and the dot and dash line 25 shows the platen at the instant it completes and leaves impression.

The object of this invention, as heretofore stated, is to so shape the curved impression surface of the platen, that from the time it partakes of the position shown at 24 and commences rolling co-action with the form, until the time when it leaves the position 25, it will have a line contact with the flat form 55 with which it co-operates and will force the paper to be printed upon, against the form at a constant pressure throughout the entire impression period.

In order to accomplish this purpose it is necessary that the curve of the impression surface be formed along accurately defined lines. I have found that the curve of the impression surface is dependent upon several factors among which may be mentioned the width of 65 the platen, the radius of the throw of the

crank shaft, and the distance from the axis of the crank of said shaft to the face of the form. If any of these factors are changed, the curve will correspondingly change, but the method of determining this curve will 70 now be fully explained so that the invention may be adapted to various conditions.

In order that the method of laying out the curve of the impression surface may be understood and practised I have, for the purpose of illustration taken seven arbitrary points on the impression surface which successively come into engagement with the surface of the form. Any number of points might be taken for example but the number 80 chosen will suffice for explanation. These seven points I have identified with the reference numerals 37 to 43 inclusive, 37 being the point of the beginning of impression and 43 a point midway of impression. On the 85 line X, which represents the height of the form, I have designated points 27 to 32 inclusive and 22 which are the points on the surface of the form with which the points 37 to 43, respectively, will successively contact 90 during the first half of an impression. Lines A, B, C, D, E, F and G are drawn from the points 27 to 32 inclusive, to the center 21 of the throw of the crank 17 and lines a, b, c, d, e, f and g are drawn from the points 95 37 to 43 inclusive, to the center 26 of the crank 17. The correct shaping of the impression surface of the platen may be computed by reference to these lines and points.

In laying out the section of the platen, as shown in Fig. 4, the distances which the spaced seven points along its impression surface are from the center 26 may be stated as a formula, to wit

Distance a=distance 27 to 21—distance 21 to 105
to 26,
or

Distance 37 to 26=27 to 21—21 to 26
or to place the formula in words:—The distance from any point on the impression surface to the center of the crank is equal to the distance from the axis of the crank throw to the corresponding point of the plane of the form surface with which the taken point of the impression surface will 110 engage during impression, minus the radius of throw of the crank, or, in other words, line A (distance 21 to 27) minus the radius of the crank throw (distance 21 to 26) equals line a (distance 37 to 26). Similarly 115 lines A, B, C, D, E, F and G minus the radius of the crank throw give lines a, b, c, d, e, f and g, respectively. The shape of correct contour for the impression surface may thus be obtained.

In other words, the distance between any particular point on the impression surface of the platen and the center of the crank 17, when added to the radius of the throw of the crank shaft 16 must be equal to the distance 120

from said shaft 16 and the corresponding point in the plane of the form with which the said point on the platen will contact during impression, and the contacting of these two points will result when the center 5 26 of the crank is oscillated into a position wherein a line drawn from the axis 21 of the shaft 16 to the said point on the surface of the form will pass through the center 10 26 of the crank.

In the manner described any and all points on the surface of the platen may be accurately and mathematically determined so that the resulting platen will be capable 15 of true and proper rolling co-action on a flat form during impression.

In accordance with the present invention, the curved face of the platen is thus shaped, so that when positively driven by the crank 20 shaft 6 and guided by the trunnions 9 all points of the impression surface will successively engage with the form and with the same pressure, so that uniform impressions result. A marked advantage of this construction in combination with the crank 25 operation of the platen is that when any point of the platen is in engagement with the form, this point is in alinement with the direct thrust of the crank on the platen.

To illustrate, it will be noted, that when the impression is being made, at the point 27 in the form, the crank 17 will be on dead center with relation to this point and, as the crank moves around to successively make 30 the impression at points 28, 29, 30, 31, 32 and 22, said crank will become successively on dead center with relation to each of said points, consecutively. When it is at the very middle of the impression, at the point 35 40 22, the crank 17 will be at its lower dead center. This construction transmits the full force of the members to the work to be accomplished in such manner as not to produce binding and allowing of very nice adjustment and accurate impressions. The machine 45 will run smoothly, without vibration, and the direct application of power to the impression surface allows the machine to be made light and consume less power than 50 when operated through indirect connections.

Through the proportioning and operation of the parts as shown and described relative to Figure 4, the period of impression of the platen constitutes a relatively small proportion 55 of the double operation thereof. As shown in this figure, the impression occupies but 60° of the rotation of the crank shaft 16 leaving 300° when the platen is off impression. This enables a printing machine 60 embodying the present invention to be run at much higher speeds than has heretofore been possible due to the fact that a maximum time is allowed for the shifting of a web between impressions, when the 65 form is stationary.

Having thus fully described the invention, what I claim as new and desire to secure by Letters Patent is:

1. In a printing machine, a printing couple embodying a flat form and a platen having a curved impression surface, and a crank for operating the platen to move it on and off impression, said platen being adapted for substantially line contact with the form during impression and the curved impression surface of the platen being of such conformation that the crank will, at all times, be on dead center with the line contact between the platen and form during impression. 70 75

2. In a printing machine, a printing couple embodying a flat form and a platen having a curved impression surface, and a crank shaft for operating the platen to move it on and off impression, said curved impression 80 85 surface of the platen being of such conformation that the distance from any point on the impression surface to the center of the crank is equal to the distance from the axis of the crank shaft to the corresponding point in the plane of the printing surface of the form with which the said point on the impression surface will engage during impression, minus the radius of the throw of the crank. 90 95

3. In a printing machine, a printing couple embodying a flat form and a platen having a curved impression surface, a crank shaft for operating the platen to move it on and off impression, and means for guiding 100 105 said movements of the platen, said curved impression surface of the platen being of such conformation that the distance from any point on the impression surface to the center of the crank is equal to the distance from the axis of the crank shaft to the corresponding point in the plane of the printing surface of the form with which the said point on the impression surface will engage during impression, minus the radius of the 110 throw of the crank. 115

4. In a printing machine, a platen provided with a curved impression surface, a crank for supporting said platen and moving it on and off impression, bearers associated with the lateral ends of said platen, means for adjusting the bearers relative to the platen to regulate the pressure of the platen during impression and means for locking the bearers in adjustment. 120

5. In a printing machine, a platen embodying a curved plate one face of which forms the impression surface of the platen, brackets projecting from the opposite face of said plate and at the opposite ends thereof to provide an operating support for the platen, and ribs or webs formed on said plate for imparting rigidity thereto. 125

6. In a printing machine, a platen provided with a curved impression surface, means 130

for actuating the platen, and trunnions for guiding the platen during its operations, said trunnions being positioned at either side of the platen with their axes in alignment with one another and projecting from the plane of the curved impression surface.

7. In a printing machine, a platen provided with a curved impression surface, means for operating the platen, and means for guiding the platen during operation, said guiding means serving to allow of oscillation of the platen on an axis passing through the plane of the curved impression surface.

8. A printing press platen provided with means for mounting it for rocking movement on an axis passing through its impression surface which is of irregular curvature in the direction of movement of the platen.

9. A printing press platen having a curved impression surface of irregular curvature and provided with trunnions at its impression surface for mounting the platen for rocking movement.

10. A printing press platen provided with a longitudinally curved impression surface embodying a succession of curves of different radii, and means for mounting the platen for rocking movement on a transverse axis substantially at its impression surface.

11. A printing press platen having an impression surface which is transversely straight and longitudinally curved on a curve struck from a moving center which most closely approaches the impression surface at a point midway of the length of said

surface, and means for mounting said platen to rock back and forth longitudinally of the platen.

12. A rocking impression platen for printing presses provided with a curved impression surface extending longitudinally of the direction of rocking movement of the platen and different portions of which surface are formed on arcs of different radii, and means for mounting the platen for rocking movement on an axis passing through its curved impression surface.

13. A printing machine embodying a flat form, a platen provided with a longitudinally curved impression surface embodying a succession of arcs struck from different centers, and means for mounting the platen for rocking movement in line contact with the form on an axis substantially at its curved impression surface.

14. A printing machine embodying a platen provided with a curved impression surface struck from the plurality of centers, and adjustable bearers associated with the opposite sides of the platen and extending substantially the full length thereof and curved to correspond with the curvature of the impression surface.

15. A printing press platen having a longitudinally curved impression surface struck from a moving center and provided at its lateral sides with aligned trunnions positioned substantially at the impression surface of the platen.

In testimony whereof, I have signed my name to this specification.

CARL A. KELLOGG,
